UNITED STATES PATENT OFFICE

VSEVOLOD G. TELLIS, OF EAST CHICAGO, INDIANA, ASSIGNOR TO O. F. JORDAN COMPANY, OF EAST CHICAGO, INDIANA, A CORPORATION OF INDIANA

WING-BRACE ARRANGEMENT FOR RAILROAD SPREADERS

Application filed December 24, 1926. Serial No. 156,790.

This invention relates to improvements in wing brace arrangements for railroad spreaders and it consists in the matters hereinafter described and more particularly 5 pointed out in the appended claims.

The primary object of the invention is to provide a novel improved wing brace arrangement for railroad spreaders wherein in 10 pairs of top and bottom braces thus bracing the top portion of the wing as well as the bottom against the load imposed upon the wing as when spreading material whereby the wing is held against a twisting action tending to 15 distort the same and its hinge plate.

A further object of the invention is to provide a novel connection between the wing brace shafts on one side of the spreader, whereby said shafts are caused to rock or turn in 20 unison so that the associated braces act together.

These objects of the invention, as well as others, together with the many advantages thereof will more fully appear as I proceed 25 with my specification.

In the drawings:—

Fig. 1 is a top plan view of a railroad spreader embodying my novel improved wing brace arrangement.

Fig. 2 is a detail vertical sectional view on an enlarged scale as taken on the line 2—2 of Fig. 1.

Fig. 3 is a transverse vertical sectional view through the spreader also on an enlarged 35 scale as taken on the line 3—3 of Fig. 1.

Referring now in detail to that embodiment of the invention illustrated in the accompanying drawings, 1 indicates as a whole the car body of a railroad spreader and 2—2 40 indicates the main or side spreader wings, with one of such wings located at each side of the car body. Each wing is pivoted at its front end to an associated upright wing post 3 on the car body, by means of a vertical axis pin 4 carried by a hinge block 5 adapted for vertical movement in the post. At each side of the car body is arranged a pair of top and bottom, longitudinally extending rock shafts 6 and 7 respectively. The ends of said shafts 45 are journalled in suitable brackets 8 and 9

respectively suitably supported from the under framing of the car body. One of said shafts is operatively connected to an associated upright power cylinder 10 on the car body by which said shaft may be rocked or turned in either direction as desired. Near the front end of each shaft is fixed an arm 11 and 12 respectively and the outer ends of both arms are connected together by a link 13 which has a bend 14 therein near the top end. As is apparent when power is applied to one 55 of said shafts (preferably the bottom one) from the cylinder 10, both shafts rock in unison. 60

Associated with each wing 2 is a front pair of top and bottom folding braces 15 and 15^a respectively, and a single rear brace bar 16. As all the folding braces are alike in construction with the exception that the rear brace is the longer, a description of one will suffice for 70 all. Each folding brace comprises inner and outer brace arms 17 and 18 respectively, the adjacent ends of which are connected together by a knuckle joint 19 which permits said bars to be folded together in the manner 75 of a folding rule. Each arm may or may not be telescopic in length, whichever manner is desired. The inner ends of the inner arms 17 of both top and bottom braces of the front pair are operatively engaged in associated sockets 80 20—20^a respectively fixed to the shafts 6 and 7 while the outer ends of the outer arms 18 of both top and bottom braces are pivotally connected as at 21 to the rear side of the associated side wing as best shown in Fig. 3. The inner end of the arm 17 of the rear brace bar 16 is operatively engaged in a socket 20^b fixed 85 to the rear end of the shaft 7 while the outer end of the arm 18 of said brace 16 is pivotally connected as at 21^a to the rear side of the side wing 2. When the rock shafts 6 and 7 are actuated in one direction, the braces fold upwardly about the associated knuckle joints into substantial parallelism as best shown at 90 the left hand side of Fig. 3, thus causing the wing to be swung in toward and parallel with the side of the car body. When the rock shafts 6 and 7 are actuated in the other direction, the braces unfold into a horizontal position, wherein the arms thereof are sub- 95 100

stantially parallel and the wing is swung into an angular position with respect to the side of the car as best shown at the bottom of Fig. 1 and at the right hand side of Fig. 3.

5 When in operation, the material being spread piles up in front of the wing and of course imposes a heavy resistance and strain thereto. Heretofore the front braces were not arranged as a top and bottom pair but 10 both the front and rear braces were connected to the wing near its bottom edge only with the result that although said bottom edge was thoroughly braced, the top edge was not. Thus the resistance of the material being 15 moved or spread acted to twist the wing longitudinally with consequent damage to itself and its associated hinge plate so that the wing would bind and not function in the manner intended. With my improved construction the top portion of the wing is braced as well as the bottom and the thrust of the 20 wing along its top and bottom portions is transmitted through the braces to the under-frame of the car body and the wing is thus held in its true intended position against twisting and there is no binding of the same at the inner end thereof. The top and bottom brace arms of the front braces on each 25 side of the car act in the manner of a folding parallelogram to always maintain the wing in the proper vertically disposed position. The bend 14 in the connecting rods or links 30 permits said rods to pass the top shafts when the braces are in the folded position as shown at the left hand side of Fig. 1.

35 While in describing my invention, I have referred to many details of construction as well as form and arrangement of the parts thereof, the same is to be considered as by 40 way of illustration and description only so that I do not wish to be limited thereto except as may be pointed out in the appended claims.

I claim as my invention:—

45 1. In combination with a railroad spreader embodying therein a car body, a side wing hinged thereto, a rock shaft journalled on the car body, a folding brace connecting one portion of the wing with said shaft, a second 50 folding brace connecting another portion of the wing with the car body and arranged in a plane above the first brace, and means causing said braces to operate in unison.

55 2. In combination with a railroad spreader embodying therein a car body, a side wing hinged thereto, a rock shaft journalled on the car body, a folding brace connecting one portion of the wing with said shaft, a second folding brace connecting another portion 60 of the wing with the car body and arranged in a plane above the first brace, and means operatively connecting said rock shaft with the second mentioned brace whereby said braces operate in unison.

65 3. In combination with a railroad spreader

embodying therein a car body, a side wing hinged thereto, top and bottom longitudinal rock shafts on the car body, top and bottom folding braces connecting the corresponding portions of the wing to said rock shafts and means operatively connecting the two shafts so they move in unison.

4. In combination with a railroad spreader embodying therein a car body, a side wing hinged thereto, top and bottom longitudinal rock shafts on the car body, top and bottom folding braces connecting the corresponding portions of the wing to said rock shafts and an arm on each shaft and a rod connecting said arms so that they move together.

In testimony whereof, I have hereunto set my hand, this 11th day of December, 1926.

VSEVOLOD G. TELLIS.
